UNITED STATES PATENT OFFICE.

HOUSTON M. CARROLL, SR., OF SAN ANTONIO, TEXAS.

COMPRESSION TRAY.

Application filed June 9, 1923. Serial No. 644,485.

To all whom it may concern:

Be it known that I, HOUSTON M. CARROLL, Sr., a citizen of the United States, residing at San Antonio, in the county of Bexar and 5 State of Texas, have invented a new and useful Compression Tray, of which the following is a specification.

By way of explanation, it may be stated that, as is well understood by those skilled 10 in the art, plaster of Paris, or other like material, contained in an impression cup frequently is used for taking impressions of the human mouth, in connection with the operation of making artificial dentures. The 15 palatine arch is much harder and more unyielding than is the alveolar ridge, and the result is that when a bite is taken on the plastic material in an impression tray, the water is pressed out of the central portion 20 of the mass, by the hard palatine arch, and flows to the edges of the tray thereby softening the material in which the impression of the alveolar ridge is received. The unsatisfactory results flowing from the foregoing 25 operation are obvious.

With the foregoing remarks, this invention aims to provide an impression tray the central portion of which is so constructed as to permit the central portion of the plastic 30 mass to yield, under the pressure of the palatine arch, so that the water will not be pressed out of the central portion of the mass, thereby softening that portion of the mass wherein the impression of the alveolar 35 ridge is received.

It is within the province of the disclosure to improve generally and to enhance the utility of devices of that type to which the invention appertains.

40 With the above and other objects in view, which will appear as the description proceeds, the invention resides in the combination and arrangement of parts and in the details of construction hereinafter described 45 and claimed, it being understood that, within the scope of what is claimed, changes in the precise embodiment of the invention shown can be made without departing from the spirit of the invention.

50 In the accompanying drawings:—

Figure 1 shows in top plan, a tray constructed in accordance with the invention;

Figure 2 is a bottom plan; Figure 3 is a side elevation; Figure 4 is a longitudinal section.

55

The tray forming the subject matter of this application preferably is made of metal and includes a body 1 comprising a base 2 and an upstanding marginal rim 3, the base 2 being arched or convexed both longitudinally and transversely, as shown in Figure 4. The base 2 has openings 4 preferably in the form of elongated slots disposed in parallel relation and extended transversely of the base, the openings terminating short of 60 the outer edge of the base, to leave an imperforate portion 5 in the base, about the outer edge of the base.

65

The handle 6 for the tray may be fashioned as desired. It may consist of a plate 70 7 having an opening 8 whereby the tray may be suspended conveniently when not in use, the plate 7 being provided at its inner end with an upstanding flange 9 joined to the rim 3 of the tray, the parts 9 and 7 being 75 distorted at their place of juncture to form reinforcing ribs 10.

75

In practical operation, the tray is filled with plaster of Paris or like material, that portion of the mass which covers the slots or 80 openings 4 being pressed through the slots to some extent by the relatively hard palatine arch an undue compression of the material being avoided, and the water being prevented from being pressed out of the mass. 85 The imperforate portion 5 of the base 2 supports that part of the mass of plastic material wherein the impression of the alveolar ridge is received.

85

ridge is received.

90

What is claimed is:

A dental impression tray comprising a base and a marginal flange projecting therefrom, the base being provided with openings which terminate short of the place of juncture between the base and the flange, to leave an imperforate portion in the base adjacent to the flange, the openings being so shaped, located, and of such a size, as to leave enough material in the base to form an adequate support for the impression material when the same is compressed against the relatively hard palatine arch, and so shaped, located, and of such a size, as to permit the impression material to retire through the 95 100

openings, and to permit the liquid in the impression material to drain through the openings, before the liquid can flow upon said imperforate portion of the base and soften 5 that part of the impression material which is engaged by the relatively soft alveolar ridge.

In testimony that I claim the foregoing as my own, I have hereto affixed my signature in the presence of two witnesses.

HOUSTON M. CARROLL, Sr.
